UNITED STATES PATENT OFFICE.

SIEGMUND LOEWE, OF BERLIN, GERMANY.

RADIO RECEIVING SYSTEM.

Application filed August 26, 1921. Serial No. 495,776.

To all whom it may concern:

Be it known that I, SIEGMUND LOEWE, a subject of the State of Germany, residing at 69 Stromstrasse, Berlin NW, Germany, have invented certain new and useful Improvements in Radio Receiving Systems (for which application has been made in the following countries: Germany, Apr. 18, 1918; Sweden, June 29, 1920, Patent No. 3,574; Great Britain, July 12, 1920, Patent No. 20,965; Holland, July 12, 1920, Patent No. 15,557; France, July 30, 1920, Patent No. 132,041; Czechoslovakia, July, 1920, Patent No. 12,745; Switzerland, 1921), of which the following is a specification.

It has been found in the operation of audion receivers which utilize vacuum tube amplifiers that there is apt to be present a local oscillation in one or more of the various circuits and that it is extremely difficult to avoid these oscillations. Even in multi-stage amplifiers which do not use an audion or a vacuum tube detector, the local oscillation could be prevented only by conductively connecting the primary and secondary of the amplifying transformer. Heretofore this procedure has not been adopted when audion detectors were employed, as such a connection would short circuit one of the audion batteries.

It is the object of this invention, therefore, to provide a circuit and connections whereby multistage amplifiers may be used in conjunction with vacuum tube detectors and the local oscillations may be eliminated by conductively connecting the primary and secondary windings of the first stage transformer.

In the accompanying drawing there is shown one of many forms of circuits to which my invention is applicable. In the circuit illustrated there is employed a vacuum tube detector having its plate connected to the antenna 5 and its grid connected in the output circuit which includes the resonant circuit 4 and the local source of energy 3. The filament of the vacuum tube may be heated by means of a battery 2.

It is to be understood that the grid or out-

put circuit includes the entire electrical path between filament and grid. In this output circuit there is connected the primary 6 of an amplifying transformer the secondary of which is connected to the grid of an amplifier tube 11. The primary 6 of this transformer is conductively connected to the secondary 7 to avoid local oscillations in the circuit. In order to make this possible without short circuiting the local source of energy 3, there is provided, according to this invention, a condenser 13 which is inserted in series with the primary winding 6. The primary 8 and the secondary 9 of the succeeding transformer are connected in the usual manner to the various circuits, and the telephone or other indicator 10 is placed in the output circuit of the amplifier tube 12.

It is to be understood, however, that the foregoing disclosure is intended merely as an illustration of one embodiment of the present invention, and is in no way limit the spirit or scope of this invention.

I claim:

1. In a radio receiving system comprising a vacuum tube detector having input and output circuits and a vacuum tube amplifier having input and output circuits; means for operatively connecting the input circuit of said amplifier to the output circuit of said detector comprising a transformer the primary and secondary windings of which are conductively connected together, and a condenser in series with said transformer primary.

2. In a radio receiving system comprising an antenna, a vacuum tube detector having an input circuit coupled to said antenna and an output circuit including a source of energy and the primary of a transformer, and a vacuum tube amplifier having an output circuit including an indicator and an input circuit including the secondary of said transformer, said transformer primary and secondary being conductively connected together; means for preventing the short circuit of said source of energy through said transformer comprising a stopping condenser in series with said transformer primary.

3. In a radio receiving system comprising a vacuum tube detector having an input circuit and an output circuit including a source of energy and the primary of a transformer,

and a vacuum tube amplifier having an output circuit and an input circuit including the secondary of said transformer; means for preventing the local oscillations of said receiving system comprising a conductive connection between the primary and secondary of said transformer, and a condenser in series with the primary of said transformer

to prevent the short circuit of said source of energy through said transformer.

In testimony whereof I affix my signature in presence of two witnesses.

DR. SIEGMUND LOEWÉ.

Witnesses:

Dr. ERICH GEINLER.
